UNITED STATES PATENT OFFICE

EDNA L. ELLIOTT, OF COLUMBUS, NEW MEXICO

CIGARETTE MENTHOLATOR

Application filed February 27, 1931. Serial No. 518,865.

This invention relates to an improved ornamental container for ready-made cigarettes, cigars, and tobacco, and it has more particular reference to a device which is expressly designed for subjecting the cigarettes to the action of mentholated vapors and fumes by a process of absorption and permeation.

More explicitly related, the inventive conception comprehends the vision of a miniature box-like container which is suitably garnished and embellished and constructed as a convenient container for loose cigarettes, means being provided therein for scenting the tobacco of the cigarettes with menthol, so that upon igniting the cigarette, it serves to diffuse a fragrant aroma, and expel a medicated smoke which serves to alleviate a certain local irritating conditions in the head and throat.

The particular structural details employed in the association of parts will become more readily apparent from the following description and drawings.

In the drawings:

Figure 1 is a vertical sectional view through a device developed in accordance with the present invention.

Figure 2 is a horizontal sectional view taken approximately on the plane of the line 2-2 of Figure 1.

Figure 3 is a vertical section at right angles to Figure 1.

Figure 4 is a top plan view of the base.

Figure 5 is a perspective view of a swingable follower.

Figure 6 is a fragmentary perspective view of a humidor wick.

The gist of the invention is founded on a structural arrangement of details mechanically co-related to provide a simple, economical and ornamental humidor for cigarettes, with a screened well in the base thereof for giving off menthol vapor and fumes to permeate and treat tobacco of the cigarettes the cigarettes being supported in the humidor in a manner to be conveniently removed.

In the drawings, the numeral 7 designates the base. This as shown in Figure 1 is provided with a marginal rectangular channel

8 and with a centralized depression 9 forming a well to receive the menthol. Over this is a covering screen 10.

The surface designated at 11 in Figure 4 is merely a clearance surface. The rectangular body portion of the box is denoted by the numeral 20, hingedly attached at 13 to the base. At an opposite point is a latch 14 carried by the base and engageable with a keeper pin 15 on the body to hold the body and base assembled.

On the interior of the box-like body is a grate 16 which is disposed horizontally at a predetermined level to divide the structure into an upper compartment 17 for the cigarettes and a lower humidifier compartment 18. In the compartment 18 and just above the well is a wick 19 designed to be moistened, particularly when cigars are placed in the compartment 17.

The lid or cover is denoted by the numeral 20 and is hingedly attached in place as at 21. The numeral 22 designates what may be referred to as a follower and this comprises a pair of arms 23 pivotally mounted in the box 12 and having a weighted cross bar 24 to rest against the perpendicular cigarettes as indicated in dotted lines in Figure 1. This swingable frame or follower is foldable back into suitable grooves 26 in the end wall of the box as indicated in dotted lines in Figure 1. Thus the box may be completely filled with cigarettes by placing them in end to end abutting relationship in a sort of stacked arrangement, as generally represented in Figure 1. The lower ends of the cigarettes merely rest on the bars or the rods of the grate 16 so that tobacco is in a position to receive the moistened vapors from the moistening wick 19 as well as the ascending and medicating vapors and fumes from the menthol containing well 9.

In actual practice, the structure may be made of wood or any suitable material, may be of any practical and enticing shape and configuration. The essential things are that it should include a suitable container for the cigarettes divided by an open-work grate into upper and lower compartments, and means in the lower compartment for supplying moisture and medicament fumes, and that

it should preferably have a follower for feeding and holding the cigarettes erect to facilitate dispensing, and that it should have a top to permit convenient insertion and removal of the cigarettes, thus providing a complete humidor and medicament applicator to fulfill the requirements of a device of this kind in a highly satisfactory manner.

10 It is thought that the description taken in connection with the drawings will enable a clear understanding of the invention to be had. Therefore, a more lengthy description is thought unnecessary.

15 While the preferred embodiment of the invention has been shown and described, it is to be understood that minor changes in shape, size, material, and rearrangement of parts, coming within the field of invention claimed 20 may be resorted to in actual practice if desired, without departing from the spirit and scope of the appended claims.

I claim:

1. In a combination humidor and medicament applicator of the class described, a base, 25 a receptacle hinged thereto, said base being provided with a medicament well, a horizontal open-work grate in said receptacle dividing it into upper and lower compartments, moistening means in the lower compartment, 30 said upper compartment being adapted to contain cigarettes in perpendicular stacked relationship, a hingedly mounted top for said receptacle, and a swingable follower in the receptacle adapted to aid in holding the cigarettes in perpendicular positions and to also 35 aid in feeding the cigarettes into close contact with one another.

2. In a cigarette dispenser of the class described, 40 a base provided with a marginal channel and a centralized depression forming a menthol containing well, a covering screen for said well, a rim-like body portion constituting a cigarette receptacle hingedly 45 mounted from said base and having its lower edge portion fitting telescopically in said channel, a plurality of longitudinally spaced parallel bars mounted in said receptacle and forming a cigarette supporting grate and 50 dividing the receptacle into upper and lower compartments, and a cover for said receptacle.

In testimony whereof I affix my signature.

EDNA L. ELLIOTT.
